CLAIM

The ornamental design for the reversible belt buckle, as shown and described.

DESCRIPTION

FIG. 1 is a top, isometric view of a reversible belt buckle showing my new design;

FIG. 2 is a rear, isometric view of the reversible belt buckle of FIG. 1;

FIG. 3 is a right side elevation view of the reversible belt buckle of FIG. 1;

FIG. 4 is left side elevation view of the reversible belt buckle of FIG. 1;

FIG. 5 is a top plan view of the reversible belt buckle of FIG. 1;

FIG. 6 is bottom plan view of the reversible belt buckle of FIG. 1;

FIG. 7 is front elevation view of the reversible belt buckle of FIG. 1; and,

FIG. 8 is a rear elevation view of the reversible belt buckle of FIG. 1.

The broken lines shown are included for the purpose of illustrating environmental structure and form no part of the claimed design.
